(57) CLAIM

I claim the ornamental design for an adjustable floor stand for use with computer tablets, as shown and described.

DESCRIPTION

FIG. 1 is a perspective top, front view of the adjustable floor stand for use with computer tablets showing my new design in use;

FIG. 2 is a perspective top, rear view thereof;

FIG. 3 is a first side view thereof;

FIG. 4 is a second side view thereof;

FIG. 5 is a front view thereof;

FIG. 6 is a rear view thereof;

FIG. 7 is a top view thereof; and,

FIG. 8 is a bottom view thereof.
